C. A. MULLEN

PAVEMENT AND METHOD OF MANUFACTURING THE SAME

Filed Feb. 9, 1925

E.P. 1.

INVENTOR.
CHARLES A. MULLEN.

By *Fetherstonhaugh & Co.*
ATT'YS.

UNITED STATES PATENT OFFICE.

CHARLES AUGUSTINE MULLEN, OF MONTREAL, QUEBEC, CANADA.

PAVEMENT AND METHOD OF MANUFACTURING THE SAME.

Application filed February 9, 1925, Serial No. 7,873, and in Canada January 5, 1925.

This invention relates to improvements in pavement and method of manufacturing the same, and in general my invention relates to that type of pavement which is constructed of 5 two or more layers of mixture, each of which mixture consists of intermingled, irregular shaped rigid mineral or other particles, such as crushed stone, gravel, slag, sand, dust, known as the aggregate, coated and cemented together by a plastic material, such as asphalt, tar, oil, known as the 10 cementing medium, in which type of pavement such a layer of mixture is spread and compressed, while sufficiently plastic, upon 15 another such layer of mixture which previously has been spread, or spread and compressed.

In particular my invention relates to that type of pavement which is constructed of 20 two or more layers of mixtures, each of which mixtures consists of intermingled irregular shaped rigid mineral or other particles, which particles, known as the mineral aggregate, are graded from some maximum 25 size down to a very small size so that, when intermingled and coated and cemented together by a bituminous cementing medium, spread and compressed, they produce a dense structure, in which type of pavement 30 such a layer of mixture, the mineral aggregate of which is graded from about one-tenth to one-quarter inch size down, is spread and compressed, while sufficiently plastic, upon another such layer of mixture, the 35 mineral aggregate of which is graded from about one to one and one-half inch size down, which previously has been spread, or spread and compressed.

It has been heretofore proposed to secure 40 an interlocking between two layers of pavement by spreading one mixture as an upper layer upon another such mixture as a lower layer without previously compressing the under layer and then compressing both 45 layers at once, while they are still sufficiently plastic.

It has also been heretofore proposed to 50 secure an interlocking between two such layers of mixture by spreading one such mixture as an upper layer upon another such mixture as a lower layer, after previously compressing the under layer only enough to turn down the points of the larger particles that protrude from the surface and then

compressing both layers at once, while both 55 layers are still sufficiently plastic.

Such methods, however, depend on the accidents of spreading for the form of interlocking and do not permit sufficient compression of the under layer immediately after 60 it is spread.

The purpose of my invention is to secure a uniform predetermined form of interlocking of such upper and under layers instead of the haphazard interlocking provided by 65 the accidents of spreading, and to permit the sufficient compression of the under layer immediately after it is spread, thus avoiding any lack of uniformity of compression due to occasional delays in spreading the upper 70 layer and the consequent stiffening of the under layer, by cooling or otherwise, before the two layers are compressed together.

My invention consists in a pavement, and in the process of producing that pavement, 75 by which I secure a predetermined form of interlocking between such an upper layer and such an under layer by impressing upon the under layer, while it is still sufficiently plastic, a pattern of raised or lowered sections or points, so that when the upper layer is spread and compressed upon the under layer, the said upper layer will engage the 80 said under layer, in the form of interlocking predetermined by the pattern.

The angles of the pattern may be so arranged as to give a form of interlocking which offers the greatest resistance to the displacement of the upper layer on the under layer by the thrust of traffic. 90

The pattern may be applied by means of a special roller carrying the pattern on its circumference, which rollers may be moved from curb to curb, or diagonally or lengthwise, over the under layer, after it is spread, 95 and while sufficiently plastic; or the pattern may be applied by means of a special tamper carrying the pattern on its face; or, the pattern may be applied by means of a special belt carrying the pattern on one side, 100 which belt may be placed over the under layer, after it is spread, and while sufficiently plastic, and the pattern on the belt imprinted on the said under layer by means of a plain tamper applied to the upper side 105 of the belt, or by any other suitable means.

When the mixture of the under layer is one having a coarse aggregate, and that

of the layer immediately above is one having a fine aggregate, the pattern may be so designed as to take advantage of the coarse particles of the mixture of the under layer so as to arrange some of these coarse particles as somewhat uniformly spaced and levelled projections between which the finer aggregate of the mixture in the layer immediately above will be present and interlocked, by being formed, through compression into correspondingly uniformly arranged projections into the layer immediately below.

The two layers which are interlocked 15 may each receive final compression separately; or the under layer may either receive but the light compression incident to the impressing of the pattern, or it may receive any degree of partial compression that 20 may be considered desirable, before the layer immediately above is spread and the two interlocking layers finally compressed together, while both are still sufficiently plastic.

25 In the attached drawings:

Figure 1 is a sectional view of a pavement embodying the present invention, and

Figures 2, 3 and 4 are diagonal views showing forms of patterns which may be 30 impressed upon the lower layer.

Referring to Figure 1, 10 indicates the top surface of any suitable foundation. A indicates the under layer mixture, compressed in place between the lines 10 and 11. 35 The line 11 represents the impression of the pattern upon the under layer mixture, which joint may be of any suitable or convenient design, such for instance as the cross corrugations indicated in Figure 2, the diagonal 40 corrugations indicated in Figure 3, and the parallel cross corrugations indicated in Figure 4.

B indicates the upper layer mixture compressed in place between the line 11 and the 45 line 12, the form of its interlocking with the lower layer A being governed by the impression of the pattern at 11. 12 represents the line of the top surface of the upper later mixture, which if desired may be given any 50 suitable surface treatment.

It will be seen that, according to the present invention, the form of interlocking is regulated by a definitely determined pattern and does not necessitate leaving the under 55 layer uncompressed or only slightly compressed until after the upper layer is spread.

It may be observed that the compression of both upper and lower layers of the pavement may be varied to suit varied conditions. 60 For instance, the compression of the under layer, prior to the spreading of the upper layer may only be sufficient to form the pattern on the top of the under layer, the final compression of both layers being effected simultaneously after the upper layer

has been spread and while both layers are sufficiently plastic.

The grading of the aggregate of each layer may be made to suit the connection of the material in hand and the condition of traffic. 70 In use I find it preferable, in the upper layer, to grade the mineral aggregate from about one-tenth to one-quarter inch size down and in the under layer to grade the mineral aggregate from about one to one and one- 75 half inch size down.

The pattern may be conveniently designed to take advantage of the coarse particles of the under layer so as to arrange some of these coarse particles as somewhat uniformly spaced and levelled projections between which the finer aggregate in the layer immediately above will be pressed and interlocked by being formed through compression into correspondingly uniformly arranged projections 85 into the layer immediately below.

It will be observed in Figure 1 of the drawings certain of the coarser particles of the lower layer project upwardly in this manner.

As many changes could be made in the above construction and many apparently widely different embodiments of my invention within the scope of the claims constructed without departing from the spirit or scope thereof, it is intended that all matter contained in the accompanying specification and drawings shall be interpreted as illustrative and not in a limiting sense.

What I claim as my invention is:

1. The herein described process of laying 100 a pavement which comprises first laying a coarser mixture designed to constitute the lower layer and comprising intermingled irregular shaped rigid mineral or other particles coated and cemented together by a 105 bituminous plastic material, then impressing upon said mixture constituting the lower layer, while sufficiently plastic, a regular pattern of raised and lowered sections or points, then spreading an upper finer layer upon 110 said lower layer, said upper layer consisting of previously mixed intermingled irregular shaped rigid mineral or other particles coated and cemented together by a bituminous plastic material.

2. The herein described pavement comprising 115 a coarser lower layer of intermingled irregular shaped rigid mineral or other particles coated and cemented together by a bituminous plastic material, and having impressed thereon while sufficiently plastic, a regular pattern of raised and lowered sections or points, an upper finer layer upon 120 said lower layer, said upper layer consisting of previously mixed intermingled irregular shaped rigid mineral or other particles coated and cemented together by a bituminous plastic material.

3. The pavement as claimed in claim 2, in 125 which the mineral aggregate of the upper

layer is graded from about one-tenth to one-quarter inch size down and the mineral aggregate of the under layer is graded from about three-quarters to one and one-half inch size down.

4. The pavement as claimed in claim 2, in which the lower layer is provided with coarse particles which, when the pattern is impressed on the lower layer, are arranged 10 to project upwardly into suitable portions of the pattern.

5. The method as claimed in claim 1, in

which the upper and lower layers are finally compressed together.

6. The pavement as claimed in claim 2, in 15 which the pattern includes parallel corrugations.

7. The pavement as claimed in claim 2, in which the pattern includes diagonally extending parallel corrugations. 20

In witness whereof I have hereunto set my hand.

CHARLES AUGUSTINE MULLEN.
